PLATE OR ANALOGOUS ARTICLE

Filed May 6, 1926

FIG. 1.

FIG. 2.

Inventor

George C. Thompson
By A. S. Patterson, Jr.

Attorney.

Patented Aug. 17, 1926.

Des. 70,866

UNITED STATES PATENT OFFICE.

GEORGE C. THOMPSON, OF EAST LIVERPOOL, OHIO, ASSIGNOR TO THE C. C. THOMPSON POTTERY CO., OF EAST LIVERPOOL, OHIO.

DESIGN FOR A PLATE OR ANALOGOUS ARTICLE.

Application filed May 6, 1926. Serial No. 17,586. Term of patent 7 years.

To all whom it may concern:

Be it known that I, GEORGE C. THOMPSON, a citizen of the United States, residing at East Liverpool, in the county of Columbiana and State of Ohio, have invented a new, original, and ornamental Design for a Plate or Analogous Article, of which the following is a specification, reference being had therein to the accompanying drawings.

The predominating feature of the design is the plurality of flat surfaces arranged at angles to one another to give an angular effect to the article. These flat surfaces stop

short of the edge of the plate and are terminated at the bottom of the plate.

In the drawings:

Figure 1 is a top plan view of the article, showing my new design.

Figure 2 is a side view thereof.

I claim:

An ornamental design for a plate or analogous article, as shown and described.

In testimony whereof, I hereunto affix my signature.

GEORGE C. THOMPSON.
